UNITED STATES PATENT OFFICE.

FREDERICK WILLIAM MILLER, OF HOCKLEY HEATH, ENGLAND.

RADIATOR-SHUTTER CONTROL.

Application filed February 8, 1928, Serial No. 252,734, and in Great Britain January 19, 1927.

This invention relates to means for controlling the opening and closing of air-shutters employed in connection with the water-cooling radiators of motor-vehicle and 5 other internal combustion engines.

The object of the present invention is to provide an improved and simplified thermostatic shutter-controlling device which is efficient and reliable in operation, is simple in 10 construction, and admits of being readily applied and fitted to a radiator.

According to the invention, the thermostatic shutter-controlling device comprises one or more thermostatic elements composed 15 of bi-metallic strips or plates mounted upon or adjacent to the radiator or cooling-water container so as to lie and move in a plane parallel to the said radiator or cooling-water container, and with the free end or ends connected to the shutter operating means. Conveniently the said thermostatic elements may be mounted above the top of the shutter adjacent the upper part of the radiator with their free ends coupled to a lever connected 20 to the radiator shutter. The lever may be of the double-arm type, and two thermostatic elements may be employed acting on opposite arms of the lever, in order that both shall assist in turning the lever in the same 25 direction.

To prevent any lag in the closing of the shutter when the water cools, an auxiliary thermostatic device may be employed which may be arranged to move, on cooling, at a 30 quicker rate or to a greater extent than the main thermostat or thermostats. This auxiliary thermostat may be arranged so that when the temperature of the water rises it has no effect on the opening of the shutter, 35 and only acts on the latter when the water cools, in order to assist in the closing of the shutter.

Figure 1 of the accompanying drawings is a front elevation of a motor-car radiator 40 shutter and thermostatic control device in accordance with this invention, the shutter being closed and the cover plate of the thermostat chamber being removed.

Figure 2 is a horizontal section on line 45 2—2, Figure 1, showing the cover plate in position.

Figure 3 is a vertical section on line 3—3, Figure 1, also with the cover of the thermostat chamber in place.

Figure 4 is a similar view to Figure 1 but 55 shows the shutter open.

Figure 5 represents a vertical section on line 5—5, Figure 4.

Referring to the drawings, the shutter comprises the usual pivoted louvres 1 mounted in a rectangular frame 2 secured by any suitable means to the front of the radiator. The louvres 1 are conveniently operated by a vertically-sliding bar 3 (see Figure 5) at one side, said bar having slots 4 in its edge engaging pins on the louvres. Fixed to the top of the shutter frame 2, so as to form a unit therewith, is an open frame 6, disposed in front of the head or top chamber of the radiator, and adapted to be closed 70 at the front by a detachable cover plate 7 (Figures 2, 3 and 5). A closed chamber is thus formed within the top frame 6 when the device is attached to the radiator, and within this chamber the thermostatic control 75 elements are placed. These elements comprise two main thermostats 8, 9, and an auxiliary shutter-closing thermostat 10, each consisting of a bi-metallic strip bent to a bow or other suitable shape and fixed at one 80 end, at 11, 12, 13 respectively, to the bottom of the top frame 6. The two main thermostats 8, 9, are made of comparatively thick metal and are disposed back-to-back parallel and close to the front of the radiator. 85 These two thermostats are arranged to act in opposite directions, that is to say, the one thermostat 8 expands whereas the other 9 contracts when heated. Their free ends are provided with slotted lugs 14, 15, which engage pins 16, 17, on the opposite arms of a horizontally-disposed two-armed lever 18 situated in front of the thermostats and pivoted at 19 to a bracket 20 on the bottom of the closed chamber. The upper end of 95 the vertical shutter-operating bar 3 extends into the thermostat chamber and carries a bracket 21 provided with a forwardly-projecting pin 22 which engages a slot 23 in one end of the lever. When the engine is 100 cool the shutter louvres are closed (as shown in Figures 1 and 3), but as the temperature

rises the one thermostat 8 expands and the other 9 contracts, their free ends acting on the lever 18 in order to lower the louvre-operating bar 3, thus opening the louvres, 5 (as shown in Figures 4 and 5).

When the engine cools the main thermostats 8, 9, return to their normal condition and close the shutters, but to avoid any undue delay or lag in this closing operation, 10 due to the thick main thermostats retaining their heat, the auxiliary thermostat 10 is provided. This thermostat is arranged to contract as the temperature rises, but it is made of thinner metal than the main thermostats, 15 thereby being more sensitive and expanding and contracting at a greater rate or to a greater extent than the said main thermostats; and being made of thinner material it does not retain its heat so long when the 20 engine cools. The free outer end of this auxiliary thermostat carries a lug 24 arranged below the lower edge of the lever, so that as it contracts on warming up, the thermostat has no influence on the lever 18, but 25 when the thermostat expands on cooling the lug 24 bears on the underside of the lever and assists to close the shutter and obviates any lag in the return of the main thermostats to their normal condition. In place of the 30 auxiliary thermostat 10 a spring could be used for assisting the closing of the shutter, but in this case the main thermostats would have to be made more powerful in order to overcome the action of the spring when opening 35 the shutter.

If desired, the shutter may be operated from both sides, another vertical bar similar to bar 3 being employed and connected to the opposite end of the lever, the pins on the louvres, however, being in front of the pivots, so that the upward movement of the bar tends to open the louvres.

Instead of the thermostats being mounted at the front of the radiator, they may be disposed at the back thereof and suitably connected to the shutter operating means.

Having fully described my invention what I desire to claim and secure by Letters Patent is:—

50. 1. The combination with an air-shutter for a radiator in the cooling-water circuit of an internal combustion engine, of a two-arm lever operatively connected to the air-shutter, and two thermostatic shutter-controlling devices each consisting of a bi-metallic heat-sensitive and deflecting member mounted adjacent to a water container in the said cooling-water circuit so as to lie and move in a plane parallel to the said container, the 55 said thermostatic devices acting in unison on opposite arms of the said lever.

2. The combination with an air-shutter for a radiator in the cooling-water circuit of an internal-combustion engine, of a two- 60 armed lever operatively connected to the air-

shutter, and two thermostatic shutter-controlling devices each consisting of a bi-metallic heat-sensitive and deflecting member mounted adjacent to a face of the radiator head so as to lie and move in a plane parallel 70 to the said face of the radiator head, the said thermostatic devices acting in unison on opposite arms of the said lever.

3. The combination with an air-shutter for a radiator in the cooling-water circuit of an 75 internal combustion engine, of a lever operatively connected to the air-shutter, a main thermostatic shutter-controlling device consisting of a bi-metallic heat-sensitive and deflecting member mounted adjacent to a 80 face of the radiator head so as to lie and move in a plane parallel to the said face of the radiator head, the said bi-metallic member having a free end acting upon the lever, and an auxiliary thermostat adapted to act 85 upon the lever in order to assist the main thermostat to close the air-shutter when the engine cools.

4. The combination with an air-shutter for a radiator in the cooling-water circuit 90 of an internal combustion engine, of a lever operatively connected to the air-shutter, a main thermostatic shutter-controlling device consisting of a bi-metallic heat-sensitive and deflecting member mounted adjacent to a 95 face of the radiator head so as to lie and move in a plane parallel to the said face of the radiator head, the said bi-metallic member having a free end acting upon the lever, and an auxiliary thermostat adapted to act 100 upon the lever in order to assist the main thermostat to close the air-shutter when the engine cools, the said auxiliary thermostat having no effect on the shutter when the temperature rises.

5. The combination with an air-shutter for a radiator in the cooling-water circuit of an internal-combustion engine, of a main 105 thermostat operatively connected to the shutter and an auxiliary thermostat operatively connected to the shutter but acting only to assist the main thermostat in the closing of the shutter.

6. A control mechanism for the air-shutter of a radiator including a lever pivoted intermediate its ends and operatively connected to the air-shutter, and thermostatic devices connected to said lever on opposite sides of its pivot and acting in unison to move the lever to thereby operate the air-shutter 115

7. A control mechanism for the air-shutter of a radiator, including a lever operatively joined to the air-shutter, a main thermostatic device connected to said lever and operable to move the same to open and close said air-shutter, and an auxiliary thermostatic device also connected to said lever to aid the main thermostatic device in closing said air-shutter. 125

8. A control mechanism for the air-shutter 130

of a radiator, including a lever operatively joined to the air-shutter, a main thermostatic device connected to said lever and operable to move the same to open and close said air-shutter, and an auxiliary thermostatic device also connected to said lever to aid the main thermostatic device in closing said air-shutter, the movement of the lever to open said air-shutter being unaffected by said auxiliary thermostatic device.

9. A control mechanism for the air-shutter of a radiator, including an air-shutter actuating member, thermostatic means for operating said member to open and close the air-shutter, and means effective only during

the closing of said air-shutter to hasten the operation of said actuating member.

10. A control mechanism for the air shutter of a radiator including an actuating member for the air shutter, two thermostatic devices differently and simultaneously affected by changes in temperature for operating said actuating member to close and open said air shutter, and means effective only during the closing of said air shutter to hasten the operation of said actuating member.

In testimony whereof I have affixed my signature.

FREDERICK WILLIAM MILLER.
